FIG. 2

UNITED STATES PATENT OFFICE

2,549,293

SHEET FEEDING AND POSITIONING
MECHANISM

Juan de la Fuente Tejedo, Madrid, Spain

Original application February 19, 1945, Serial No. 578,653. Divided and this application February 11, 1948, Serial No. 7,693. In Spain January 15, 1944

3 Claims. (Cl. 197—127)

1

This application is a division of my application entitled "Electric Machine for Typing in the Braille and Abreu Systems," Serial No. 578,653, filed February 19, 1945, now Patent No. 2,454,637 dated November 3, 1948.

This invention relates to sheet feeding and positioning mechanism as used in electrically operated typewriting machines for embossing paper according to the Braille and Abreu code systems devised for use by the blind.

Machines of this type have been known commercially for many years, as instanced by the Llorens, Braille, Abreu and other makes.

Such machines generally included a group of embossing rods operated singly or in various combinations by depressible keys.

The Braille system employs a six-point code, that is, a group of six paper-indenting rods is arranged beneath the paper, and in line with an anvil overhanging the ends of the indenting rods. The paper advances between the free ends of the indenting rods and the anvil.

Depression of the appropriate keys projects the free ends of the indenting rods against the paper, forcing the latter against the anvil or platen. The anvil may be provided with a series of recesses in register with the free ends of the respective indenting rods, and the impact of the selected rods against the paper forces the latter against the anvil, the free ends of the rods pressing the paper into the corresponding recesses in the anvil to indent the paper with a code representation of a particular letter, numeral or symbol.

In those typewriting machines employing a six-point code, the keyboard may have but six keys, each of which is individual to its respective indenting rod, in which event, combinations of keys must be depressed in the majority of instances, where the code representation of a letter, numeral or symbol comprises more than one indentation.

Other machines are provided with a full keyboard, that is, with individual keys for the several letters, numerals and symbols. In these machines, means are provided to enable certain of the keys, upon depression, to operate two or more of the indenting rods, it being obvious that with the employment of a six-point code, certain of the keys must actuate at least five indenting rods, and one key may have to operate all six indenting rods, depending upon the number of different code representations to be formed.

This requires the operator to exercise more pressure on some of the keys than on those which

2

are required to operate but a single indenting rod only. This induces uneven fingering of the keys and leads to mistakes, particularly disadvantageous in this type of machine wherein the erasure of improper representations is difficult, if not impossible, and entails more care on the part of the operator.

To remedy this unevenness of touch, these machines have heretofore been provided with electrically operated power devices, as electromagnets of different types individual to their respective indenting rods, for projecting the rods, the keys upon depression merely serving to close one or more circuits arranged in proper combinations with the several electrically operated power devices.

These attempts have not avoided the unevenness of touch, however, since the circuit combinations are closed by rocking single spring-restored levers in some instances, by the pressure exerted upon the selected key, whereas, in the majority of instances, the selected key must rock two, three, four, five and possibly six spring-restored levers to form the desired code representations.

Therefore, one object of this invention is to provide, in a typewriting machine having electrically operated means to indent paper in accordance with a legible code, a keyboard, the keys of which may be depressed by an even equal pressure, to select any one or more of the individually operable indenting means for operating in forming the code representations corresponding with the letters of the alphabet, numerals and punctuation marks.

In attaining this object, the structures of the prior art have been greatly simplified by eliminating the systems of levers heretofore selectively operated singly or in various groups by the manually depressed keys, and instead, the letter, numeral and symbol keys of the keyboard operate traveling contacts which serve to close the various combinations of circuits required in the selection for operation of the proper combinations of indenting rods to form code representations corresponding with the letters, numerals and symbols appurtenant to the particular keys depressed.

In designing machines for use by the blind in typing Braille code, it is highly desirable that tactile-sensible means be provided for use in the event that it becomes necessary for the operator to remove a partially-coded sheet from the typewriting machine and then to replace the sheet in the machine in such exact adjustment that the

writing may be re-commenced at the point where it ceased prior to the removal of the sheet.

Another object of this invention is the provision of novel and simplified means readily operable to accomplish this result.

A further very desirable feature for incorporation in typewriting machines for use by the blind is the provision of means, including a tactile-sensible mark, or marks, which will enable the operator, when preparing to write on the back of a sheet already indented on its face, to correctly introduce and position the sheet in the machine in such manner that the indented code lines to be impressed on the back or rear face of the sheet shall be staggered, offset or interspersed relatively to the indented lines previously formed on the face of the sheet.

Therefore, still another object of this invention is the provision of novel and extremely simple marking means used in combination with the last-mentioned means which enables the correct re-insertion of a partially written sheet, the novel marking means enabling the operator through his sense of touch to position the sheet, already indented on its face, in such manner that the lines of indentations to be impressed on the back of the sheet shall be "interprinted" or interspersed relatively to the lines of indentations on the face of the sheet.

Other objects and advantages will be more fully explained in the following specification and particularly pointed out in the claims.

Because the above improvements are applicable to Braille code typewriting or indenting machines old and well known in the art, it has seemed unnecessary to set forth in detail any but the main features of the old machines with which the novel mechanisms have been combined, to enable a proper understanding of the invention and its location with respect to such old and well-known features.

Therefore,

Fig. 1 is a diagrammatic and conventionalized view in side elevation of the right side of any of the well known forms of electrically operated Braille writing machines, equipped with the invention;

Fig. 2 is a detailed view showing one of the writing keys of a full keyboard writing machine with a conventional disclosure of the circuits for energizing two electro-magnets controlled by the particular key;

Fig. 3 is a detail top plan view of the pressure roll mechanisms, and

Fig. 4 is a detail view in side elevation of the pressure roll mechanism.

Since the invention is intended for application to any of the well known embossing machines equipped with electrically operated embossing mechanisms, for use by the blind, the several novel features have been shown as applied to a conventional diagrammatic view, and it is to be understood that such view may be considered as a disclosure of any of said machines, except for such elements as constitute the present invention.

Therefore, referring to Fig. 1, the machine includes a main frame 1 provided with rails 1a to support a traveling carriage 2 for letter spacing travel and return.

A full capacity keyboard is provided comprising character keys 7 representing any one or more notational systems, as the English alphabet, the ten digits, and various punctuation marks, or the like.

A space bar 10 which, with the keys 7, controls any well known form of letter spacing mechanism, not shown, in use on machines of the kind mentioned, may be conveniently positioned at the extreme front end of the main frame and in a lower plane than the character keys, as is customary.

Because of the area required to represent the notational characters in tactile-sensed Braille or other code to facilitate such tactile sensing by the blind, machines for writing Braille and similar codes are preferably provided with letter-spaced escapements arranged to space the code characters a greater distance apart than are legible typewritten characters.

For these reasons, also, the line spacing mechanisms of Braille and similar code-writing machines provide wider spacing between the lines.

The electrically-operated embossing mechanism shown in dotted lines in Fig. 1 and in full lines in Fig. 2 is merely a diagrammatic showing of the electro-responsive devices 10, the actuating levers 11, 11, for the group of individually operable embossing rods 11a, 11a guided for vertical sliding movement in a turret 14 projecting upwardly from a table 13 mounted in the main frame of the machine near its rear end.

Embossing machines for writing Braille characters employ a six-unit code, the impressions or indentations representing the Braille characters being formed by any, and in one instance all, of six embossing rods 11a (Figs. 1 and 2) arranged in two straight parallel lines of three indentations each, which lines may be vertical or horizontal in relation to the writing line.

The form illustrated in the accompanying drawings shows the horizontal parallel arrangement of the embossing rods, and hence the right side view of the machine. Fig. 1 shows the two spaced embossing rods at the right hand end of the double line of three rods each.

Likewise, Fig. 1 shows only the two right hand actuating levers 11 for said two right hand embossing rods 11a and the two right hand electro-responsive devices, as the electro-magnets 10, it being understood that there are two additional pairs each of electro-magnets, actuating levers and embossing rods behind, that is, to the left of those indicated in Fig. 1.

Obviously, these elements could be arranged according to the more common form wherein the embossing rods lie in two parallel rows of three units each to form code characters vertically in relation to the writing line.

Returning to the description of the machine as shown, the electro-magnets 10, 10 are suitably supported in the main frame 1 beneath a table 13.

The aligned pairs of oppositely extending actuating levers 11, 11, are pivotally supported intermediate their ends at 11b, 11b, by individual hangers 11c, 11c, depending in pairs from the under side of the table 13.

Armatures 10a, 10a, pivotally depend from the respective remote ends of the pairs of levers to overhang the cores of the electro-magnets, the proximate ends of the respective pairs of actuating levers being enlarged or lobed at 11d, 11d, to form peens which strike against the soles of off-set or splayed feet 11e, 11e, fast on the lower ends of the vertical embossing rods 11a.

The pairs of feet are downwardly and outwardly inclined from their points of attachment to the lower ends of their individual embossing rods 11a, to afford room between the bottom of

the table 13 and the upper surfaces of the feet for the compressed springs 80 which by pressing against the feet, yieldingly retain the embossing rods 11a in their lowered positions.

The soles of the feet, in turn, press against the lobed ends 11d of their actuating levers 11 to rock the armatures 10a away from the cores of their corresponding electro-magnets. Guide pins 71 project upwardly from the free ends or toes of the splayed feet 11e into holes formed in the bottom of the table 13 to assist in guiding the embossing rods 11a and to hold the feet in proper position.

Abutments 81 depending from the bottom of the table 13, limit the spring-actuated movement 15 of the levers 11.

The six-unit group of embossing rods project vertically upward through apertures in the table 13 and through guide ways in the vertically projecting turret, which guide ways are aligned with the apertures in the table.

The turret projects upwardly into the space between the side frames of the paper carriage 2, the upper end of the turret terminating at a plane substantially horizontal with the planes of the highest points of a set of lower paper feed rolls 16 (Figs. 1, 3 and 4) spaced along a paper-feed roll shaft 15 extending between and journaled in the end frames of the paper carriage 2.

Hand rolls or twirlers 5 mounted on the projecting opposite ends of the paper feed roll shaft 15 enable the operator to rotate the shaft and its rolls 16 to advance the paper in line spacing direction and to reversely feed the record sheet, as desired.

Peripherally knurled pressure feed rolls 17 journaled on the rear ends of rearwardly projecting leaf springs 17a press the work sheet against the respective knurled paper feed rolls 16.

The forward ends of the leaf springs 17a are carried by a cross rod 82 extending between the side frames of the paper carriage.

Conveniently, the paper feed rolls 16 lie adjacent to, and directly in front of the upper end of the embossing rod turret 14, as shown in Fig. 1. An anvil 4a depends from a rearwardly extending curved horn 4 which suspends the anvil directly over the upper end of the turret 14 and spaced slightly apart therefrom to afford passage for the record sheet. Customarily the lower free end of the anvil is provided with a series of recesses each of which is in line with its corresponding embossing rod 11a. The forward end of the curved anvil supporting horn 4 is firmly secured to the main frame of the machine just in rear of the keyboard, as is customary.

A hollow cylindrical paper holder or paper holding scroll, indicated by dotted lines 83 in Fig. 1, is mounted in the depending front side of the traveling carriage 2. This paper holder may be of the form used in the Hammond Typewriting machine, or may be like that shown in U. S. patent to Kurowski et al., 1,767,247, June 24, 1930, to which reference is also made for an approximation of the paper feed roll mechanism above described.

The work or record sheet 84 may be rolled into a loose coil and inserted endwise from one end of the paper carriage into the paper holder, from which the leading edge of the sheet is led through the paper throat 84 along the paper apron 85 between the paper feed rolls 16 and pressure feed rolls 17, thence between the recessed lower face of the anvil 4a and the upper end of the embossing rod turret 14 to the sheet aligning and

adjusting means, and thence out of the rear of the paper carriage.

To enable the work sheet to pass freely between the paper and pressure rolls 16, 17, when inserting and adjusting the sheet, a pressure roll cast-off is provided, which, as shown, comprises a pressure roll cast-off shaft 86 extending between and journaled in the ends of the paper carriage 2, on which shaft are fixed a plurality of cam members 87, one cam member beneath and in line with its appropriate leaf spring arm 17a carrying a pressure feed roll 17.

In their normal rest positions these cast-off or pressure roll release cams 87 lie out of effective relation with their spring leaf arms, but upon manipulating a pressure roll cast-off handle 88 fast on a projecting end of the release shaft 86, the release cams 87 are forced against the leaf spring arms 17a from beneath to rock the arms upwardly and disengage all pressure rolls 17 from the co-acting paper feed rolls 16 to enable the record sheet to pass freely therebetween.

It will be understood that the paper apron 85 is apertured or cut away at the proper points to permit the operation of the pressure roll cast-off cams 87, and also to clear the work sheet feed rolls 16, as shown in dotted lines in Fig. 1, and the upper end of the embossing rod turret 14.

The foregoing is, in a general sense, old in the art, the mechanisms above described forming a part of the invention so far as they co-act therewith in the accomplishment of the novel results of the invention now to be set forth.

Referring to Fig. 2, a conventional circuit diagram is shown, one pole of a source of electrical energy, as the battery 13, being connected to the two electro-magnets 10 there illustrated, similar conductors leading to the remaining four of the entire series of six electro-magnets, as indicated by the trailing ends of four conductors.

The notation-representing keys 7 open and close the circuits according to a predetermined code, the code being well known in the art, and hence, not illustrated.

The application of this code to the notation or character keys 7 and the controls exercised by the keys on the circuits will be explained in connection with the key mechanism embodying one feature of this invention.

As heretofore stated, one object of this invention is the provision of a light and even key touch.

As one means to effect this result, each key 7 comprises a key top 7a, mounted on the upper end of a stem 7b, to the lower end of which stem is fixed a non-cylindrical plunger 7c of suitable insulating material.

The plunger 7c is contained in a guide which, as shown, consists of a non-cylindrical tubular housing 9 to prevent rotation of the key relatively to its housing, it being understood that there is a separate housing for each key.

The upper end of each housing 9 is closed except for an aperture through which the key stem projects, to form a stop against which the upper end of the plunger strikes to arrest the travel of the key at its normal elevated position. The lower end of the plunger is contacted by one end of a coiled key-restoring spring 89, the opposite end of which rests on the bottom of the housing.

One wall of the housing is cut away or slotted longitudinally, as at 90 (Fig. 2), and flanged arms 91, 91 projecting from the slotted side of the housing, engage and hold an insulated, con-

tact-point supporting block 8 closely against the slotted side of the housing.

Each of these insulated supporting blocks is provided with from one to six contact points 92 secured in any convenient manner in a vertical row registering with the slot or opening 90 in the housing 9. Fig. 2 illustrates that key housing having five contact points.

The contact point or points 92 are insulated from each other and each contact point is in circuit with its individual electro-magnet 10.

A lead connects the key housing 9 with the other pole of the electrical source B, it being obvious that the several housings can be electrically connected so that a single lead only is required. The housings are insulated from the main frame of the machine in any convenient manner, not shown.

The key plunger 7c, of insulating material, is provided with a diametrical bore 93 extending from that side of the non-cylindrical plunger which lies in contact with the slotted wall of the housing 9 to the opposite side of the plunger.

Two contacts 94, 95, shown as globular in shape, are carried in this bore or aperture, between which contacts is placed a spring 96 to retain the contacts at the respective outer ends of the aperture. One of said contacts 94 engages the adjacent inner face of the housing, the other contact 95 being protruded from the aperture a sufficient distance by the spring 96 to extend through the slotted opening 90 in the housing and wipe over the insulated contact point or points 92 mounted in the insulating supporting block 8 upon depression of the key.

It will be appreciated that the contacts 94, 95 and spring 96 carried by the key constitute a contact member travelling with the key to close and open a circuit or circuits individual to the respective electro-magnets 10.

It will be noted also that in those instances where the key, upon depression, closes more than one circuit, the circuits are closed successively and not simultaneously, thereby greatly reducing the strain on the anvil caused by the impact of the upper ends of the embossing rods 11a thereagainst.

The operation of the embossing mechanism under control of the character keys 7 may be understood from the foregoing description.

It will be understood that the several character keys 7 and their housings are exactly similar, the only difference being in the number of stationary contact points 92 arranged for engagement by the respective keys, and hence the number of particular electro-magnets which are energized and the number and pattern of the code character impressed in the work sheet by the embossing rods 11a.

The provision of six individually operable embossing rods and their actuating electro-magnets having individual circuit connections permits of some forty-two permutations, thus enabling a like number of different code symbols to be embossed to represent the letters of the alphabet, the ten numeral digits and some of the punctuation marks. For example, depression of the character key 7 representing "a" might result in the formation of a small boss on the writing line of the sheet; depression of the character key representing "b" might result in the formation of two bosses in the sheet vertically arranged one directly above the other. Obviously, this would mean that the insulated supporting block 8 associated with the character key "a" carries a

single contact point 92 only, whereas the supporting block associated with the character key "b" carries two contact points in circuit with two separate electro-magnets controlling the actuation of two embossing rods, one behind the other, as viewed in Figs. 1 and 2, and so on.

Pressure of the operator's finger on a key top 1a depresses the corresponding plunger 7c in the housing 9 and compresses the key-restoring spring 89. The plunger, during its descent in the housing, wipes its traveling contact 94, 95, 96 over the contact point or points 92 on the insulated supporting block 8 to close successively (assuming two or more contact points are engaged) the individual circuits leading to the appropriate electro-magnets 10 to effect successive energization thereof.

The electro-magnets thus energized attract their armatures 10a, causing the actuating levers 11, 11a to drive the associated embossing rods 11a, 11a upwardly against the record sheet and anvil, to form a code character corresponding to the notational character of the depressed key.

Assuming the selected key to be one co-acting with a plurality of vertically arranged contact points 92, the escape of the traveling contact 94, 95, 96 past the first contact point engaged, opens the circuit through the particular electro-magnet appurtenant to such contact point, whereupon the corresponding embossing rod restoring spring 80 becomes effective to lower its embossing rod 11a to normal idle position and in so doing, rock the actuating lever 11 back to its normal position to disengage the corresponding armature 10a, from the core of its electro-magnet, such action occurring as the traveling contact escapes past all the stationary contact points.

Removal of pressure on the depressed key 7 enables the key restoring spring 89 to return the key and its traveling contact past all the contact points 92 until the traveling contact comes to rest above the uppermost contact point.

Obviously, the identical embossing rods 11a are thus again operated, though in reverse order, during the return of the depressed key, but since the letter-spacing mechanism (not shown) while tripped, is not permitted to operate until the traveling contact escapes past the uppermost stationary contact point, the only result is to provide a more deeply incised impression of the code character in the work sheet.

Reference has been made to the provision of means enabling the operator to correctly position and align the work sheet, not only preliminary to commencing to write thereon, but also when it is desired to reinsert a partially written sheet into the machine and start writing where the previously written matter stopped, and also when it is desired to write on both sides of a sheet.

In the last-named event, care must be taken to emboss the lines written on the back of the sheet at such places as will not confuse the tactile sensing of the written matter on both sides of the sheet, bearing in mind that the indentations on one side of the work or record sheet result in projections on the opposite side, and it is the projections arranged in code representations that are to be sensed.

Consideration will first be given to the means provided for correctly positioning the work sheet in the machine preliminary to writing thereon, and for arranging for the re-insertion of the sheet in case of its removal from the machine

prior to completing the writing thereof, which constitute another feature of this invention.

After the coiled work sheet is inserted end-wise into the hollow cylindrical paper holder 83, its leading edge is drawn through the paper throat 84 and rearwardly along the paper apron 85.

The operator, having first rocked the handle 88 to lift the pressure rolls 17 off the sheet feeding rolls 16, continues to draw the leading end of the sheet rearwardly through the gap thus formed between the sheet feeding and the pressure rolls and through the passage between the lower recessed face of the anvil and the upper end of the embossing rod turret 14.

It then becomes necessary to correctly position the sheet in the machine in order that it may be fed in a straight line rearwardly out of the machine, to which end, there is provided a novel means for "squaring" the leading edges of successive sheets in position and to afford a uniform top or leading end margin.

These results are effected by the provision of a pair of angularly formed gage members 97 (Fig. 1) pivotally intermediate their ends at 98 to the inner faces of the paper carriage end frames. The forward arms of the pivoted gage members extend to points immediately beneath eccentrics 99 mounted on the pressure roll cast-off shaft 86 for operation with the pressure rolls. The rear arms of the gage members support upwardly extending registering or aligning pins 6, and at a suitable distance in front of each pin, these rear arms support an upright indenting stylet 100, the stylets being of slightly less height than the gage pins 6.

Springs 101 connected to the gage pins 6 normally draw the respective gage members 97 clockwise relatively to the position shown in Fig. 1, when the pressure roll cast-off handle is in its ineffective position, and the pressure rolls 17 engaged with the feed rolls 16. In such normal clockwise positions, the upper ends of the pins 6 and their stylets 100 lie in a plane beneath the path of the work sheet to afford no obstruction to the advance of the sheet in letter spacing direction.

But when the pressure roll cast-off handle is rocked to its effective position, to raise the pressure rolls 17, the eccentrics 99 on the pressure roll cast-off shaft 86 wipe over the front arms of the gage supporting members to rock the members counter-clockwise and position the aligning or gage pins 6 across the path of the leading edge of the sheet as it is led rearwardly preliminary to adjustment.

At this time, the sheet is but loosely held in the machine and the operator can manually shift it until the opposite corners of the leading edge of the sheet contact the long gage pins 6 to "square" or correctly position the sheet in the machine.

The counter-clockwise movement of the gage frames 97 results in positioning the upper free ends of the stylets 100 directly beneath the sheet, and after the operator has adjusted the sheet relatively to the gage pins, he presses the sheet downwardly over the stylets to form indentations or punctures in the sheet at points just a short distance below the leading edge of the sheet.

Such indentations or punctures will result in forming projections on the upper face of the sheet, which serve two purposes, as soon explained.

After the top margin of the sheet has thus been indented or punctured, the cast-off handle 88 is restored to its normal position, permitting the spring pressure roll arms 17a to cause the pressure rolls to grip the work sheet, and as the eccentrics 99 release the forward arms of the gage frame 97, the springs 101 rock the gage frames with their aligning pins 6 and indenting stylets 100 clockwise to withdraw the pins and stylets from the path of the sheet.

Writing on the sheet may now proceed, it being clear that the punctures formed in the top margin of the sheet by the stylets are well beyond the first writing line of the sheet.

It may become necessary, after having partially completed the writing of the sheet, to remove the sheet from the machine, and later, to replace the sheet and complete the writing from the point where the sheet was removed.

The provision of the top margin punctures by the stylets 100 greatly facilitates this operation.

The partially written sheet is reinserted and aligned with the gage pins 6 just as before explained. This, however, is not sufficient as there is no proof to the operator that the sheet is in the original position laterally with respect to the working lines so that there will be no difference in the side margins of the sheet. By providing the stylets 100, however, which have been elevated to their effective positions when re-inserting the partially written sheet, the operator by his sense of touch can feel the punctures formed in the top margin, and can shift the sheet sideways until the leading edge is still held against the gage pins 6, until the top margin punctures register with the upper ends of the stylets, after which the pressure roll cast-off handle may be rocked to enable the pressure rolls to become effective and to permit the springs 101 to rock the gage frames to their idle positions. Then by advancing the sheet in line spacing direction by the twirler 5, the last previously written line is brought to the writing point, and the writing completed.

It may be desired to write on both the front and back sides of a sheet in which event, as above explained, it is necessary to so position the sheet when it is inserted for writing on the rear face thereof, that the lines of indented Braille code characters are interspersed, staggered or "interpointed" relatively to the previously written lines on the front of the sheet.

The above-mentioned top margin punctures, in combination with means now to be described, are utilized in positioning the sheet to effect such interspersal of the lines of writing on the respective opposite sides of a single sheet.

A cross shaft 102 extends between and is journaled in the end frames of the traveling carriage 2 at a point above the path of the sheet, such cross shaft supporting a pair of indenting members 103 arranged transversely of, and fast on the shaft with their pointed ends projecting forwardly to positions overhanging the upper ends of the stylets 100 and located preferably about the distance of half a line space in advance of the stylets when the latter are in their effective positions. Springs 104 normally hold the indenting members 103 in their upraised idle positions, a finger piece 105 fast on a projecting end of the cross shaft 102 enabling the operator to rock the shaft and its indenting members counter-clockwise to form punctures in the top margin of the sheet at points, say, half a line space

11

nearer the first writing line than the punctures formed by the stylets.

When the operator desires to write on both sides of the sheet, when positioning the sheet in the first instance, as above explained, he will not only puncture the sheet by means of the stylets 100, but will also manually rock the finger piece 105 to cause the indenting members 103 to puncture the top margin at points half a line space nearer the first writing line.

Thereafter, the operator will proceed as heretofore explained until the front side of the sheet has been written, whereupon he will reverse the sheet side-for-side and re-insert it in the machine in the manner explained. At this time, however, instead of registering the stylet-formed punctures on the stylets and abutting the leading edge of the sheet against the gage pins 6, he will slide the leading edge of the sheet upwardly over the gage pins until he can register the punctures formed by the indenting members 103 with the stylets, which not only squares the sheet and properly positions it relatively to the side margins, but also enables the first written line on the back of the sheet to be located half a line space beneath the first written line on the front of the sheet.

The pressure rolls, when returned to their effective positions, retain the sheet in its newly adjusted position and permit the gage frames and stylets to "disappear," that is, return to ineffective position.

Attention is directed to the fact that the punctures formed by the stylets and those formed by the indenting members are opposed to each other as regards the projecting portions thereof, and lie at different distances from the leading edge, which difference is readily sensed by the operator who can thus assure himself as to which side of the sheet is front or back.

The paper apron 85 is apertured to permit the gage pins 6 and stylets 100 to shift upwardly to be controlled by the sheet.

I claim:

1. In an embossing machine of the typewriter class, the combination with a main frame; a paper carriage mounted to travel thereon; grouped embossing members mounted in the main frame; an anvil superposed above the grouped embossing members to afford a passage therebetween for the work sheet; and pressure feed roll mechanism mounted in and traveling with the carriage to support and advance the work sheet; of a normally idle leading edge gage mounted in the paper carriage to shift into and out of the path of the leading edge of the work sheet at a point beyond the grouped embossing members, to provide a top margin of suitable depth; an indenting member located between the leading edge gage and the grouped embossing members, said indenting member being shiftable with the leading edge gage into and out of effective position; and means to cast off the pressure roll mechanism and incident thereto, to shift the leading edge gage and the indenting member into operative relation with the work sheet, to arrest the leading edge of the work sheet after it has passed beyond the indenting member, and thus enable the operator by slight pressure on the work

12

sheet, to form an indentation therein, which indentation, upon the replacement of the work sheet in the machine, may be registered with the indenting member to facilitate the relocation of the work sheet in the position to which it was originally adjusted.

2. In an embossing machine of the typewriter class, the combination with a main frame; a paper carriage mounted to travel thereon; grouped embossing members mounted in the main frame; an anvil superposed in line with the grouped embossing members and spaced apart therefrom to afford a passage therebetween for the work sheet; and pressure feed roll mechanisms mounted on and traveling with the carriage to support the work sheet and advance it in line spacing direction; of a leading edge gage shiftable into and out of the path of the work sheet at a point in line spacing direction beyond the grouped embossing members; a normally idle indenting member also shiftable into and out of effective position relatively to the leading edge of the work sheet to enable the operator to indent the work sheet on one side thereof; a second normally idle indenting member shiftable to indent the opposite side of the work sheet at a predetermined distance in line-space direction from the point at which the first-named indenting member is effective, to enable the operator to replace the sheet face downward in the machine, and by registering the second-named indentation with the first-named indenting member, to position the sheet so that the embossed lines on the back of the sheet will be interspersed or interpointed relatively to the embossed lines on the face of the work sheet, and means to operate said second named indenting member.

3. In an embossing machine of the typewriter class, the combination with an embossing mechanism; and a pressure feed roll mechanism to support a work sheet and feed it in line spacing direction past the embossing mechanism; of a leading edge gage shiftable into and out of the path of the leading edge of the work sheet to determine the depth of the top margin; a pair of indenting members arranged on the respective opposite sides of the work sheet to form indentations on the respective opposite sides of the sheet, said indentations being formed a predetermined distance apart substantially equal to half a line space, to enable the operator to reverse the work sheet face down for reinsertion in the machine, with the indentation formed by one of said indenting members in register with the other of the indenting members, whereby the embossed lines on the two sides of the sheet will be relatively interspersed or interpointed; and means to shift the indenting members into and out of their respective effective positions.
